UNITED STATES PATENT OFFICE.

CLAYTON O. STONE, OF BROOKLYN, NEW YORK.

DESIGN FOR A GAME-BOARD.

51,516.

Specification for Design.

Patented Nov. 20, 1917.

Application filed October 5, 1917. Serial No. 194,992. Term of patent 7 years.

To all whom it may concern:

Be it known that I, CLAYTON O. STONE, a citizen of the United States, residing at Brooklyn, in the county of Kings and State of New York, have invented a new, original, and ornamental Design for a Game-Board, of which the following is a specification.

Referring to the drawing—

The figure is a perspective view of a game board, showing my new design.

I claim:—

The new, original and ornamental design for a game board, substantially as shown.

In testimony, that I claim the foregoing as my own, I have hereto affixed my signature in the presence of two witnesses.

CLAYTON O. STONE.

Witnesses:

GEORGE A. NAGEL,
HARRY ESTERMAY.
